UNITED STATES PATENT OFFICE.

JOHN C. BROOKS, OF PATERSON, NEW JERSEY, ASSIGNOR, BY MESNE ASSIGNMENTS, TO DRAPER COMPANY, OF HOPEDALE, MASSACHUSETTS, A CORPORATION OF MAINE.

LOOM.

SPECIFICATION forming part of Letters Patent No. 732,043, dated June 30, 1903.

Application filed February 1, 1900. Serial No. 3,863. (No model.)

To all whom it may concern:

Be it known that I, JOHN C. BROOKS, a citizen of the United States, residing at Paterson, in the county of Passaic, State of New Jersey, have invented an Improvement in Looms, of which the following description, in connection with the accompanying drawings, is a specification, like letters on the drawings representing like parts.

10. My invention is an electric loom, being particularly adapted for silk-weaving, although capable of use for general weaving purposes, and is preferably an electrical adaptation of the form of loom shown in my 15 United States Patent No. 473,377, granted April 19, 1892.

In silk-weaving particularly there is so much nicety of action and adjustment required that most of the work is still done by hand, and the automatic looms have made very slow headway, one reason therefor being that silk-weaving requires very accurate tension on the thread, this not being so required in cotton-weaving, and also the prejudice and preference of the silk-weavers for the old methods has necessitated certain styles of apparatus which have long since disappeared in connection with cotton-weaving. Accordingly I have devised the present 20 form for accomplishing automatically the required results in silk-weaving, (and likewise in all other kinds of weaving, as may be desired,) my invention including, preferably, a tension device and also including the automatic supplying of filling to the shuttles by 25 means of electrical connections. I have also provided a special means for preventing uneven or improper position of the cop or thread mass within the shuttle, and various other 30 improvements and advantages of my invention will be pointed out in the course of the following description, reference being had to the accompanying drawings, illustrative of a preferred embodiment of my invention, and 35 the latter will be more particularly defined in the appended claims.

In the drawings, Figure 1 is a fragmentary view from the left side, partly in section, showing a sufficient portion of a loom to enable my invention readily to be understood.

Fig. 2 is a front elevation thereof. Fig. 3 is a top plan view thereof. Fig. 4 is a view similar to Fig. 3, the filling-carrier being removed for the purpose of showing the feeler and adjacent mechanism. Figs. 5 and 6 are 55 respectively views of the shuttle in top plan and front elevation. Fig. 7 is a cross-sectional view thereof on the line 7-7, Fig. 5. Figs. 8 and 9 are respectively views in longitudinal section and end elevation of a quill or cop included in my invention. Figs. 10, 11, and 12 are respectively views in top elevation, longitudinal, and cross section of the tension device. Figs. 13, 14, and 15 are 60 perspective views of details to be referred to. 65

While I have shown my invention applied to one particular form of broad loom, it will be understood that with slight modifications it may be adapted for various other kinds of looms.

The loom side a , breast-beam a' , lay a^2 , lay-sword a^3 , binder or swell a^4 , shuttle a^5 , picker-stick a^6 , dagger a^7 , frog a^8 , reed a^9 , reed-rail or hand-rail a^{10} , and various other details of construction may be of any usual or preferred kind and will not, therefore, be further referred to.

At one end of the loom-frame above the breast-beam I mount a filler-carrying mechanism, shown as of the endless-belt or card variety of my patent before mentioned and comprising forward and rear sprocket-wheels b and chains b' , carrying small clips b^2 and springs b^3 , substantially the same as in my aforesaid patent, and carried in brackets b^4 85 of peculiar construction. On the outer end of one of the axles b^x of one set of sprocket-wheels b I mount a ratchet-wheel b^5 , engaged by a pawl b^6 , pivoted in an arm b^7 , loosely mounted on the axle or shaft b^x and connected freely at its end by a link b^8 with a crank b^9 , extending upwardly (see Fig. 1) from a rock-shaft b^{10} , journaled at the front of the filling-changing mechanism, as clearly shown in Fig. 2. The shaft b^{10} is normally held in 90 the position shown in Fig. 1 by a spring s and has fixed thereon two upwardly-overhanging arms b^{12} , which serve as actuators for an ejector or discharge plate b^{13} , mounted in vertical ways b^{14} , provided in the ends b^{15} of the brack- 95

ets b^4 for the purpose of discharging or ejecting the filling or fresh bobbins into the shuttle when the filling of the latter has been exhausted, or nearly so, said ejector and arms 5 being connected by links b^{16} . At its right-hand end, viewing Fig. 2, the shaft b^{10} has a crank or rocker arm b^{17} , pivoted at the free end of a lever b^{18} , (see Fig. 1,) normally resting on a stop b^{19} in the adjacent loom side. 10 The latter lever b^{18} carries at its rear free end a second lever b^{11} , pivoted thereto at b^{20} , said lever having a forward L-shaped end b^{21} , normally resting beneath the lever b^{18} and projecting into the path of a depending end b^{22} 15 of a lever b^{23} , pivoted to the loom side and carrying an armature b^{24} at its rear end, and the lever b^{11} has a forked rear end b^{25} , adapted to engage a bunter c , secured to any suitable part, being herein shown as fastened 20 rigidly to the lay a^2 . The forked end b^{25} of the lever b^{11} is normally below the line of movement of the bunter c and is only in the path of said movement when raised thereinto by the lever b^{23} , which at such time is raised 25 by the attraction of its armature by the electromagnet b^{26} , which is mounted on a bracket b^{27} , bolted to the frame of the machine, said bracket, as herein shown, also serving to support a feeler d , comprising two arms d^1 d^2 , 30 loosely pivoted together and held against stops d^3 d^4 by springs d^5 d^6 . (See Fig. 4.) The feeler is preferably metallic and insulated from its supporting-bracket, and at its free end enters a usual opening e in the shuttle-box e' , said feeler operating in general the 35 same as feelers commonly provided.

The shuttle a^5 is shown in Figs. 5 and 6 and in general is constructed the same as usual, excepting as its form is required to be 40 changed in order to receive and retain the bobbin or filling carrier and filling-case and tension device, as will be presently explained, and contains a plurality of spring-clips f , (shown in detail in Fig. 7,) said clips coöperating with depressions y in a filling-case g , which I prefer to specially provide in connection with the filling, as will be more fully pointed out. The filling-case g is preferably made of metal and carries a metal spindle g' , 45 hinged at g^2 and operating in substantially the same manner as the kind of bobbin-holders sometimes provided in shuttles, although it will be understood that I do not restrict myself to this form of bobbin-support, as any 50 other usual or preferred device for this purpose may be employed within my invention, and, indeed, broadly considered, I do not restrict myself to the filling-case, although for silk-weaving it is much preferable. The 55 shuttle has a hole f' , adapted to aline with the hole e in the shuttle-box for the entrance of the feeler, and adjacent said hole I have shown a contact-plate f^2 , having connection by a wire f^3 (indicated in dotted lines in Fig. 60 5) to the end spring f within the shuttle and against which the metal case g bears when in the shuttle.

In silk-weaving, as already mentioned, it is necessary to have uniform and accurate tension, and I have found that the tension is often varied by the twisting or incorrect positioning of the bobbin within the shuttle, as if the bobbin is slightly to one side the thread will not draw off evenly, but will draw off harder on one side than it does on the other, and this unevenness will produce disastrous results, especially at the edge of the web being woven, (as loom-temples are not ordinarily used in weaving silk.) I have therefore devised a construction in which the 70 length of the bobbin is materially shortened, thereby not only minimizing the irregularity of tension which would be produced if the bobbin should get out of true alinement, but also rendering the latter less liable to become deflected out of true position by the filling changing or ejecting movement of the filling-changing apparatus, said bobbin being shown in Figs. 8 and 9 at h , from which it will be seen that it is relatively very thin 75 vertically in cross-section and wide horizontally, having a correspondingly-shaped opening h' to receive the spindle g' and a narrow neck h^2 to receive fresh filling to run one or two picks, if necessary, after the filling has 80 become exhausted sufficiently to bring the electrical contacts into operation. This construction permits a much greater amount of thread to be wound on the bobbin for a given length and a given vertical diameter or thickness than otherwise possible, or, in other words, I am enabled to wind the required 85 amount of thread on a very short bobbin 90 close to the supporting end of the shuttle and yet without getting it thicker or greater 95 in diameter than is adapted for the shed, and thus the advantageous results pointed out 100 above are secured. At the heel end of the bobbin I secure a contact-spring h^3 , connected by a wire h^4 to a metal boss h^5 , which 105 comes in contact with the spindle g' when the bobbin is placed in position, said contact-spring h^3 being normally covered by the 110 thread when the filling is freshly supplied to the shuttle and remaining covered until the 115 filling is exhausted sufficiently to make it desirable to supply a new filling and discharge 120 the exhausted one.

At the right-hand end of the shuttle I have 120 shown my tension device above mentioned, said tension being herein shown as carried by the filling-case g and comprising a plate g^3 , hinged to lugs g^4 , Fig. 10, and normally held under closing pressure by a spring g^5 , 125 said plate having a plurality of depending notched ribs or flanges g^6 , which coöperate with projections g^7 projecting upwardly from bottom of the case g , and also, preferably, I 130 suspend auxiliary notched plates g^8 adjacent the ribs g^6 , said plates g^8 being carried by a band g^9 of rubber or other resilient material. The thread (indicated at g^{10} , Fig. 11) is maintained under the desired tension by being caused to pass in the irregular path indicated,

being thence threaded through a hole or other suitable aperture g^{12} and passing out of the shuttle through a rearwardly-oblique notch g^{13} .

5 Another advantage of my tension is the facility with which it is threaded, it only being necessary to throw up the plate g^3 and simply lay the thread along the notches of the flanges g^7 and then permit the plate to snap down by reason of its spring g^5 , whereupon the thread is immediately placed under tension. The free end of the thread is held prior to the filling being automatically placed in the shuttle by any suitable spring-clips b^{30} , Fig. 3.

15 It will be understood that I have omitted a multitude of constructional details common to looms and that I have not shown any of the usual operating mechanism, inasmuch as any common operating mechanism may be used, either such as shown in my before-mentioned patent or any other loom construction.

25 I have already explained the main connections of the electric circuit, it being understood that any suitable source of supply, as a battery w , will be provided at any suitable location, being connected by wires $w' w^2$ with a plate w^3 on the shuttle-box and with the 30 electromagnet, respectively, a wire w^4 leading from said electromagnet to the feeler, and through the latter the circuit is completed by contact with spring h^8 , thence through wire h^4 , spindle g' , case g , end spring 35 f , plate f^2 to plate w^3 , &c.

In operation, the bobbin having been wound with weft, so as to retain the spring h^8 in an 40 obvious manner, and placed in the shuttle-case, as shown in the drawings, the free end of the thread is dropped on top of the notches of the ribs g^7 and the tension-plate is allowed to whip over on top thereof, the thread being then caught in the notch or hole g^{12} , and the free end thereof is slipped into the spring b^{30} , 45 the case being placed in proper position on the traveling sprocket chain or belt of the filling-supplying mechanism. As the lay is operated in usual manner, the shuttle being shot back and forth through the shed, the filling will soon become exhausted, and as soon 50 as it becomes sufficiently so to release or expose the spring h^8 the latter will upon the proper pick be engaged by the feeler as the lay comes forward on its front center, and the 55 moment that the feeler and spring h^8 come into contact the electric circuit is thereby completed, energizing the electromagnet b^{26} . The latter instantly raises the armature b^{24} of the lever b^{23} , thereby depressing the end b^{22} 60 thereof, so as to raise the forked end b^{25} of the lever b^{21} into the path of the bunter c just be-

fore the latter reaches engaging position therewith, whereupon the two come in contact, and the further forward movement of the lay rocks the shaft b^{10} over rearwardly, so 65 as to depress the ends of the arms b^{12} , and thereby forcibly lower the ejector b^{13} and press or shove the end filling-case and its contained filling, &c., into the shuttle, at the same time discharging from the latter the exhausted filling-case. As the filling was inserted into the shuttle-box the ratchet-arm b^7 was by the same movement moved around to the left, Fig. 1, on the ratchet-wheel, so that when the lay went back, thereby withdrawing 70 the bunter from engagement with the fork b^{25} , the spring s caused the ratchet-wheel b^5 to rotate, so as to bring a second filling and filling-case into position beneath the transfer or ejector b^{13} all ready to be put into 75 the shuttle whenever the previous filling became in turn exhausted. This cycle of movements is automatically repeated as the filling becomes exhausted.

It will be understood that various forms of 85 filling-carriers and of supplying and changing mechanisms may be employed and that also my invention includes changing the shuttles electrically, if desired.

Various other changes than those above 90 mentioned may be resorted to within the spirit and scope of my invention.

Having described my invention, what I claim as new, and desire to secure by Letters Patent, is—

1. In a loom, a tension device movable with the shuttle comprising a case having a hinged plate, said case and plate each having a plurality of ribs arranged respectively opposite to each other, the filling being received between said opposite ribs, and auxiliary plates yieldingly supported adjacent certain of said ribs to bear yieldingly on the filling. 95

2. In a loom, a filling-case adapted to receive and support a bobbin, said filling-case 105 having a tension device comprising a hinged plate, means normally holding said plate downwardly, a plurality of notched ribs on said plate, a plurality of projections fixed in said case opposite said ribs, a yielding device 110 extending longitudinally from rib to rib, and auxiliary plates freely suspended from said yielding device and normally depending slightly below the upper edges of said projections. 115

In testimony whereof I have signed my name to this specification in the presence of two subscribing witnesses.

JOHN C. BROOKS.
